CLAIM

I claim the ornamental design for a modified phone clip, as shown and described.

DESCRIPTION

FIG. 1 is an exploded front perspective view of the modified phone clip with rear plate and front clip plate;

FIG. 2 is a perspective view shown assembled;

FIG. 3 is a rear perspective view shown exploded;

FIG. 4 is a front elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a front elevation view of the inner side of the rear plate disclosed in FIG. 1.

FIG. 10 is a perspective view of the front clip plate thereof;

FIG. 11 is a rear perspective view of the front clip plate thereof;

FIG. 12 is a rear elevation view of the front clip plate thereof;

FIG. 13 is a front perspective view of the inner rear plate thereof;

FIG. 14 is a rear perspective view of the outer side of the rear plate thereof;

FIG. 15 is a rear elevation view of the outer rear plate thereof; and,

FIG. 16 is a perspective view of the design shown in use.

1 Claim, 16 Drawing Sheets
